UNITED STATES PATENT OFFICE.

AMBROSE S. STEBBINS, OF NEWARK, NEW YORK.

CAKE-TIN.

SPECIFICATION forming part of Letters Patent No. 468,073, dated February 2, 1892.

Application filed May 25, 1891. Serial No. 394,032. (No model.)

To all whom it may concern:

Be it known that I, AMBROSE S. STEBBINS, of Newark, in the county of Wayne and State of New York, have invented a new and useful Improvement in Cake-Tins, which improvement is fully set forth in the following specification and shown in the accompanying drawings.

The object of my invention is to produce a contractible cake-tin by means of which thin circular cakes of different diameters may be baked for the purpose of making laminated cakes, and also to provide the cake-tin with a removable cone center to facilitate the removal of the cake therefrom.

The invention is hereinafter fully described, and more particularly pointed out in the claims.

Referring to the drawings, Figure 1 is a view of the interior of a cake-tin, a part of the bottom being broken out and the hoop shown in two positions by full and dotted lines. Fig. 2 is a side elevation of the device with a part of the hoop broken out. Fig. 3 shows a similar though deeper cake-tin with a removable cone, a part of the hoop being broken away. Figs. 4 and 5 show different-sized bottom plates for the device. Fig. 6 shows a slight modification in which a channel is formed for a part of the hoop to slide in. Fig. 7, drawn to a larger scale, is a cross-section on the dotted line 7 in Fig. 6.

Referring to the parts shown, A is the hoop or band of the cake-tin, divided longitudinally at one side with the ends lapping upon each other.

B are bottom plates for the tin, which are made in several sizes to correspond to the hoop when differently contracted. I prefer to make three or more of these bottom plates of different diameters for the purpose of baking layers for pyramidal cakes.

The upper edge of the hoop is formed with a bead *a*, except as to the part *b*, which laps upon the outside of the other part *f* of the hoop.

The hoop is formed with an inwardly-turned flange *c* to hold the bottom plates B. These bottom plates are circular, each being formed with a peripheral projection *d*, and the hoop is formed with horizontal slots *e* just above the flange *c*, out through which said parts *d*

project, as shown in Fig. 1, when the parts are put together.

There is but one slot in the inner end *f* of 55 the hoop, but three or more are formed in the outer end *b*, every one of these slots in the part *b* being capable of being brought to correspond with the slot in the part *f* as the hoop is variously contracted. By this means 60 the hoop may be contracted to various diameters, a bottom plate being provided for each position of the hoop.

The bead *a* is preferably formed over a wire core *g*, Fig. 7, and is left for a distance slightly 65 open below the wire, as shown, to form a channel *h*, in which the plain part *b* of the hoop may slide when the latter is contracted or expanded. This keeps the part *b* of the hoop snugly against the part *f* in whatever 70 position the hoop may be relating to the matter of its contraction.

With the deeper bake-tins (shown in Fig. 3) a removable cone *i* is employed, the lower end *l* of which is made cylindrical to fit 75 within a circular down turned flange *k* of the bottom plate B. The cone fits the flange snugly so as to hold to place by friction; but it may be easily pushed downward through the bottom plate and removed therefrom, as 80 indicated by its position shown in dotted lines.

The hoop A and bottom plate with the cone are preferably made of sheet-tin, like other similar devices.

What I claim as my invention is—

1. A cake-tin consisting of a hoop or band divided at one side, with its ends lapping upon each other, and a removable bottom plate for said hoop, the bottom plate having a peripheral projection and the hoop being formed 90 with openings through its overlapping ends in which to receive said projection of the bottom plate, substantially as shown and described.

2. A cake-tin consisting of a contractible 95 hoop or band divided at its side, with its ends *b* and overlapping, said end *f* being formed with a horizontal slot and the end *b* being formed with a series of similar slots, so that when the hoop is variously contracted the slots in the 100 end *b* will successively correspond with the slot in the end *f*, and a bottom plate having a projection at its edge to enter said slots, substantially as and for the purpose set forth.

3. A cake-tin consisting of a hoop divided at one side, with its endslapping upon each other, and a removable bottom plate for said hoop, the bottom plate having a peripheral projection and the hoop being formed with openings through its overlapping ends in which to receive said projection of the bottom plate, the hoop being formed with a bead, and a channel therein in which to receive the outer overlapping end of the hoop, substantially as described.

4. A cake-tin consisting of a hoop or band divided at one side, with its endslapping upon each other, and a removable bottom plate

having a peripheral projection, and the hoop 15 being formed with openings through its overlapping ends in which to receive said projection of the bottom plate, the latter being provided with a removable cone, substantially as set forth.

In witness whereof I have hereunto set my hand, this 13th day of May, 1891, in the presence of two subscribing witnesses.

AMBROSE S. STEBBINS.
